UNITED STATES PATENT OFFICE.

MARSHAL C. RHODES, OF ASHLAND, LOUISIANA.

VENDING-MACHINE.

1,372,550.

Specification of Letters Patent. Patented Mar. 22, 1921.

Application filed January 26, 1918. Serial No. 213,933.

To all whom it may concern:

Be it known that I, MARSHAL C. RHODES, a citizen of the United States, residing at Ashland, in the parish of Natchitoches and 5 State of Louisiana, have invented certain new and useful Improvements in Vending-Machines, of which the following is a specification.

This invention relates to new and useful 10 improvements in vending machines, and more particularly a new and improved machine of this character, that is operated by a coin, and which comprises an article holder, and mechanism for ejecting an article from 15 the magazine upon a coin being placed in the machine.

A further object of the invention is to 20 provide a very simple and efficient type of vending machine of this character, which is especially adapted for vending chewing gum, small candy, or the like, and which machine is entirely automatic in operation, inasmuch as upon placing a coin in the coin chute, the same operates the article discharging 25 mechanism, so that the lowermost article in the magazine is discharged, and also the next article is dropped down into position, so that the machine is always operative as long as the magazine contains the articles 30 to be vended.

A further object of the invention is to 35 provide a device of this character, which is easily and simply constructed, inexpensive to manufacture, and one which will be very efficient in operation.

With these and numerous other objects in view, my invention consists of the novel features of construction, combination, and arrangement of parts which will be herein 40 referred to and more particularly pointed out in the specification and claim.

In the accompanying drawings:

Figure 1 is a perspective view of the machine,

Fig. 2 is a horizontal section,

Fig. 3 is a rear view with the back removed,

Fig. 4 is a side elevation with one side removed, and

Fig. 5 is a fragmental detail of the tripping mechanism.

In describing my invention, I shall refer to the drawings in which similar reference characters designate corresponding parts 55 throughout the several views.

The numeral 1 designates the casing of my new and improved vending machine, which may be formed of any desired material, preferably metal, said casing having a hinged front 2, which is pivoted at its lower edge, and positioned within the casing adjacent the front face thereof, is a hinged magazine or container 3, which is provided with a partition 4, dividing the same into two upright compartments. Any number of 60 compartments may be employed as desired, by increasing the size of the casing, and providing a discharging mechanism for each compartment. The lower or front face of the casing is open, and is provided with a 65 projecting shield portion 5 that guides the articles discharged from the casing, and which likewise prevents unauthorized tampering with the internal mechanism of the machine, by persons inserting their hands, or 70 sticks or the like through the open front thereof. This pivoted construction of the front 2, permits the same to be swung outwardly, so that the refilling is greatly expedited, and likewise renders the coin receiving 75 chamber easily accessible.

The rear portion of the casing 1, which is designated by the numeral 6, extends outwardly, from the upper edge to the lower edge, to provide an enlarged chamber for a 80 purpose to be hereinafter more fully described. The opposite sides of the casing are provided with parallel coin chutes 7, which extend from an opening in the upper edge thereof down into the coin receiving 85 chamber 8, which is preferably lined with a rubber, felt or any other sound deadening material. The rear walls of the chutes, are provided with apertures 9, communicating with the enlarged rear side of said casing, 90 and likewise having their front ends opening into the coin chutes 7.

The article discharging mechanism employed in this type of vending machine, comprises a pivoted lever 10, having its upper portion 11 substantially straight, and pivoted as shown at 12 at its upper end, said straight portion likewise being provided with a projecting lip 13, that is normally disposed within the opening 9, and hence having its inclined upper face 14 disposed across the coin chute. The lower portion of the lever 10 is bent inwardly as shown at 15, and the lower extremity thereof is provided with a pushing fork or yoke 16, which is disposed 105 110

beneath the lowermost article in the magazine 4, when the lever is in normal position. A coil spring 17 connects the lever, intermediate its ends with the rear wall of the casing 5 for a purpose to be hereinafter more fully described.

In the accompanying drawings, I have shown the machine as comprising a magazine formed with two upright chambers 10 therein, but it is obvious that any number of chambers may be employed as desired, providing each chamber has a discharging mechanism co-operatively related therewith. Separate mechanism is employed for each 15 of the chambers shown in the accompanying drawings, but as the mechanism is exactly alike, I have only specifically described one of the same for the sake of brevity.

20 In operation, when the various parts of the device are in normal position, as clearly shown in Fig. 1 of the drawings, and the articles to be vended are positioned in the container or magazine, upon the insertion 25 of a coin in the coin chute 7, through the opening in the top of the casing or side wall thereof, the coin will drop down, and its weight will be sufficient, that upon its coming into engagement with the projecting 30 lip 13 on the lever 10, to force the lever rearwardly, within the enlarged portion 6 of the casing, and hence withdraw the fork. The lever 10 will then be thrown into the 35 position shown in dotted lines in Fig. 4 of the drawings, and the spring 17 will be compressed. Immediately upon the fork portion of the lever being removed from beneath the article, one article will drop down into the space formerly occupied by 40 said fork, and after the coin passes the lip, the spring will force the lever back into position, and the fork moving forward will engage said article and project the same forwardly through the open portion in the 45 front of the casing. This will throw the article out through the discharge chute 5, to the purchaser.

The operation of this type of vending machine is very simple, and the small number of movable parts employed in the discharging mechanism, does not detract from the efficiency of the device in any manner. Its operation is entirely automatic, and the operation of the coin controlled discharge mechanism is thoroughly reliable. The inclined back permits the machine to be attached to theater seats or the like.

50 From the above description, taken in connection with the accompanying drawings, it is thought that a clear and comprehensive 55 understanding of the construction, operation, and advantages of my invention may be had, and while I have shown and described the device as embodying a specific structure, I desire that it be understood that 60 such changes may be made in said structure as do not depart from the spirit and scope 65 of the invention as claimed.

Having fully described my invention, what I claim as new, and desire to secure by 70 Letters Patent, is:

In a vending machine of the class described, an upright stationary article holding magazine provided with a plurality of vertical compartments, coin chutes arranged 75 laterally and at each side of said compartments, ejecting levers pivotally supported in the upper part of said magazines and provided with coin engaging, projecting 80 lips extending within the coin chutes whereby the levers may be actuated by a coin falling vertically within the chutes, each 85 of said levers extending inwardly and downwardly terminating in a right angled forked yoke positioned in the bottom of the compartments for supporting the articles to be vended, and contractile springs normally 90 holding the yokes within the compartments and adapted to eject the lowermost article during the return movement of the said yokes after the levers are actuated.

In testimony whereof I affix my signature hereto.

MARSHAL C. RHODES.
